SIMULTANEOUS TRANSMITTING AND RECEIVING SYSTEM WITH ELECTRONIC CHANGE-OVER DEVICE

Werner Hasenberg, Rio de Janeiro, Brazil

Application January 22, 1941, Serial No. 375,492
In Brazil December 2, 1940

1 Claim. (Cl. 179—1)

The present invention refers to a system of simultaneous transmission and reception by means of which the restrictions which are up to now imposed by self-excitation (regeneration) will be removed.

The best known system of simultaneous transmission and reception is the telephone system and, for a better understanding of the present invention, the characteristics of the telephone are explained below.

Each telephone set consists of a transmitter, represented by the microphone, and a receiver, represented by the earphone. A simultaneous transmission and receiving process requires at least two parties or two telephone sets respectively.

Due to the fact that the telephone sets are continuously in condition to either transmit or receive (talk and listen), either party is able to express himself whenever he wants to.

The telephone system of present design is working on limited energy, and, therefore, the earphone has to be brought near the ear and the microphone near the mouth.

The intercommunicating system is based on working conditions similar to those of the telephone system utilizing nearly the same basic elements. The intercommunicating system also represents a transmitting and receiving system, but not a simultaneous one. Another difference between the telephone and the intercommunicating systems is that the latter has to be operated by means of a talk-listen switch which disconnects the receiving circuit while connecting the transmitting circuit, and vice versa. It is well known that advantages as well as disadvantages result from using this switching device. The advantage consists in the possibility of transmitting and receiving an almost unlimited energy-level, whereas the disadvantage is that transmission and reception are consecutive and not simultaneous. Comparing the transmitting and receiving operation of the telephone system with that of the intercommunicating system, it is noted that the telephone system means simultaneous operation whereas the intercommunicating system means consecutive operation. As to energy, it has to be kept in mind that the telephone system is working on a limited energy level, whereas as the intercommunicating system allows for applying a high energy level.

The reason for limiting the energy level (telephone system) or desisting from the simultaneousness of transmission and reception by using a talk-listen switch (intercommunicating system) is an electro-acoustical phenomenon called "regeneration." No regeneration is observed in the telephone system because of the limited energy level, nor does any possibility of regeneration exist in the intercommunicating sys-

tem because of the absence of a closed circuit and because of a talk-listen switch device which changes over to one or the other direction.

The following detailed description should be read in conjunction with the accompanying drawing, in which

Fig. 1 shows an electro-acoustically "closed" circuit consisting of two transmitters and two receivers working simultaneously in duplex.

Fig. 2 shows one of the possible circuits according to the invention, demonstrating in what manner the control of the modulator amplifier operates and how it controls a second amplifier connected to the former amplifier.

Fig. 3 complements Fig. 2 showing, diagrammatically according to the invention, the connection, in duplex operation, of both transmitters and receivers and their mutual control.

Fig. 4 is a graphic representation of the instantaneous values of conductivity or amplification as a function of time during the four phases of the duplex operation.

The above phenomenon of "regeneration" is analysed in Figure No. 1, showing a closed intercommunicating circuit.

The initial energy produced by microphone M—1 is amplified by transmitter T—1 and receiver R—2 and is then received by loudspeaker A—2. A part of this energy emitted by A—2 enters microphone M—2 and is then conducted to transmitter T—2 where the energy is again amplified. Receiver R—1 receives this energy amplifying it once more and conducting it to its loudspeaker A—1. This electro-acoustical closed circuit becomes self-oscillating entering in regeneration, in case part of the energy emitted by A—1 reacts again on M—1.

The present invention which represents a system of simultaneous transmission and reception by means of an electronic changeover device, combines the advantages of the telephone system with those of the intercommunicating system and eliminates their disadvantages, thus making transmission and reception possible: (a) simultaneously and (b) with energy theoretically unlimited.

The simultaneous transmission and reception system—according to this invention—utilizes an automatic control device which reduces amplification of the second party's transmitter at the moment the first party starts to transmit, and vice versa. In other words, the transmitter of the receiving party is automatically decreased to such an extent that it becomes impossible to have the manifestation retransmitted to the sending party. Due to this system, regeneration is not possible because the entire amplification never reaches a level which would allow such regeneration. The amplification of all units, transmitters and receivers which are connected to the sys-

tem, remains during non-operation on an energy-level not sufficient for exciting the closed circuit to become self-oscillating (regeneration). Exclusively at the transmitter which is transmitting and only during the time of transmission, the amplification level is higher than the level of non-operation.

On Figure No. 2 which shows one of the various possible circuits, the manner of operation is explained.

The microphone is connected to input E of the amplifier, and the loudspeaker to output S. A voltage divider C—R₀ is shunted to the plate circuit of output tube V—3. The voltage drop across resistor R₀ originated by the amplified microphone current is rectified by diode tube D (control device). The rectified voltage on its turn, is conducted, as follows: One part is fed to the junction of resistors R₂—R₃ situated in the grid circuit of tube V₂. The other part is conducted to terminal Z. It should be noted that the rectified voltage at Z is negative, and that over R₃ it is positive in relation to the ground level of the amplifier, i. e. that the potential at Z and R₃ will be decreased or increased respectively, proportionate to the modulation produced by the microphone connected at E (Fig. 2). The entire circuit of the transmitting or receiving system has to be completed by the second party's set which is of identical design to that demonstrated on Figure 2 and in this way a circuit is obtained as shown on Figure 3.

Assuming that the total level of amplification of the entire electro-acoustical circuit M₁—A₂—M₂—A₁ is aligned in such a manner that the absolute stability is guaranteed in the initial phase (phase of non-operation), i. e., there is no regeneration possible, and one of the parties starts transmitting, the following will happen:

For instance, M₁ starting transmission, causes automatically an increase of amplification of its own transmitter (demonstrated by tubes V₁—V₂—V₃) due to decrease of the negative grid polarization of tube V₂. This will result in a high level reception in loudspeaker A₂ pertaining to the second party. Simultaneously—and this is the essential point of this invention—the operating microphone M₁ of the first party will automatically cause decrease of the transmitting level of the second party because of the high negative polarization in the grid circuit of tube V₁. This tube is identical to tube V₁, shown on Figure 2. The polarization from the first party to the second party is conducted by line Z—Y'.

When the second party replies to the call received utilizing microphone M₂ (Fig. 3), the same process will be repeated, as follows:

Increase in amplification of second party's transmitter;

Decrease in amplification of first party's transmitter.

During this operation period, the control is made across line Z—Y.

When the operation of transmitting and receiving between both parties is finished, the am-

plification of the entire circuit will automatically be reestablished at the initial level according to the nonoperative phase.

On Figure 4 the mutual control is explained with reference to this simultaneous transmission and reception system, in accordance with this invention; furthermore, the shape of the instantaneous levels of amplification or conductivity of both parties during the four phases, is demonstrated.

I. *Phase of non-operation*.—The amplification in one as well as in the opposite direction of the transmitting and receiving system is established at a level which guarantees the stability of the entire circuit; this means, that the sum of both levels represented by the respective ordinates reaches a previously determined value.

II. *Phase of transmission in the direction of M₁ to A₂ (Fig. 3)*.—At the moment the amplification increases in the transmitting direction as shown in Figure 4 upper curve, the amplification decreases in the opposite direction (transmitter actually not transmitting), as shown in Figure 4 lower curve.

III. *Phase of transmission in the direction of M₂ to A₁ (Fig. 3)*.—In this phase of operation, the lower curve belongs to the actually transmitting transmitter and shows a higher level than the curve which belongs to the non-operating transmitter.

IV. *Phase of non-operation (Fig. 4)*.—This phase is identical to phase I.

The conclusion of these explanations is that the transmission and reception system, in accordance with this invention, is a simultaneous one and is improved by the possibility of operating at energy levels theoretically illimitable. This improvement is obtained by means of an automatically and instantaneously working control of the conductivity or amplification of the electrical system, there being established, at any moment, a total amplification level in both directions of the process which will never reach the critical value of the regeneration level.

I claim:

A system of transmission and reception of sound consisting of, two channels of opposite direction, each channel comprising a microphone and a loudspeaker and an electronic device self-contained with amplifying means operating as A-type amplifiers and control means for the mutual control of the gain in either channel so as to reduce the gain in its own channel when a direct current potential is impressed and produce a rectified direct current potential when sound energy is transmitted through the channel, both means providing that the overall gain in the two channels is kept below the level of self-oscillation due to acoustic feed-back in the absence and presence of actual transmission, an outlet for the control potential which is to act on the opposite channel, and an inlet grounded for alternating current but receptive for a direct current potential to be applied from outside.
